BOLSTER CASING FOR SPINNING SPINDLES

Filed Feb. 9, 1923

UNITED STATES PATENT OFFICE.

HJALMAR G. CARLSON, OF WORCESTER, MASSACHUSETTS, ASSIGNOR TO ROCKWOOD SPRINKLER COMPANY OF MASSACHUSETTS, OF WORCESTER, MASSACHUSETTS, A CORPORATION OF MASSACHUSETTS,

BOLSTER CASING FOR SPINNING SPINDLES.

Application filed February 9, 1923. Serial No. 618,146.

To all whom it may concern:

Be it known that I, HJALMAR G. CARLSON, a citizen of the United States, residing at Worcester, in the county of Worcester and 5 State of Massachusetts, have invented a new and useful Bolster Casing for Spinning Spindles, of which the following is a specification.

This invention relates to a bolster casing 10 intended to be used for holding a spinning spindle.

The principal objects of the invention are to provide a casing of this kind formed from sheet metal and provided with a projection 15 around it integral with the sheet metal of which the rest of the casing is made and having an oil-receiving depression in it; to provide this in such form that it can be constructed by die-pressing operations and 20 at a very rapid rate, materially decreasing the cost of production and also doing away entirely with the projection ordinarily employed at this point on cast iron bolsters; and to provide means by which the bolster 25 can be adjusted minutely to an exactly vertical position and held in such position positively and firmly.

Additional objects of the invention will appear hereinafter.

30 Reference is to be had to the accompanying drawings, in which—

Fig. 1 is a side view of a spinning spindle located in a bolster casing constructed in accordance with this invention;

35 Fig. 2 is a central sectional view of the same;

Fig. 3 is a sectional view of the upper part of the bolster casing on the horizontal line 3—3 of Fig. 2;

40 Fig. 4 is a similar view showing the doffer guard in position, and

Fig. 5 is a side elevation showing the operation of the doffer guard.

I have shown the invention as applied to 45 an ordinary rail 10 of a spinning machine, this rail having a perforation 11 therethrough for the bolster casing 12. This perforation is larger than the intermediate portion of the bolster casing so as to permit of 50 adjusting the casing to the exact vertical position.

The bolster casing is formed of a single

piece of sheet metal pressed up in dies to provide the desired construction. It comprises a lower end 13 closed at the bottom by 55 a bottom wall 14 having an inward depression or step 15 therein for receiving the bottom end of the spindle. It also has an upper end 16 of substantially the same size and shape as the lower end but open at the 60 top to receive the spindle. Between these two end portions 13 and 16 there is an intermediate portion 17 of a larger diameter, screw threaded on its outside surface.

The two parts 16 and 17 have formed at 65 their junction an oil cup 18. It is formed by two thicknesses of metal pressed first outwardly and then inwardly into contact with the outer layer to form this annular oil cup. This provides a circular space surrounding 70 the bottom of the upper portion 16 of the bolster casing to receive oil put in intentionally or accidentally discharged over the open end of the bolster casing. The wall is provided with a perforation 19 to allow the oil 75 to run down into the interior where it will lubricate the spindle, being received in the space between the spindle and the enlarged intermediate portion 17 in the casing. This oil cup 18 is therefore of annular form 80 having double walls and a horizontal rim.

A flat doffer guard plate 20 is arranged to rest on the top of the oil cup. This plate has a downwardly extending flange 21 all around it. It has a central perforation 22 85 for receiving the lower flange 30 on the bottom of the whirl 31 of the spindle. The oil cup is provided with a pair of headed studs 23 located diametrically opposite each other, the outer walls of the cup being preferably 90 slightly flattened where they are provided to receive a pair of opposite flanges 21 parallel to them. These flanges are provided with vertically elongated slots 24 through which the studs 23 pass, and they 95 are so located that when the plate 20 rests on the top of the cup 18 these slots extend below the studs.

On one end of the plate 20 there is provided a cylindrical offset 25 in which is 100 permanently fixed a wire 26 which extends upwardly and is provided with an inwardly and downwardly extending hook 27 constituting a doffer guard and projecting up

over the upper horizontal flange 32 of the whirl normally.

The lower surface of the cup 18 is convex preferably and under this is located a sheet metal washer 28 which has a concave upper surface fitting the bottom of the cup. The bottom of the cupped edge of this washer is squared up and rests horizontally on the top of the rail 10. Underneath the rail there 10 is another cupshaped sheet metal washer 29 and fitting the convex lower surface of it is a nut 33 which has a concave or internal spherical upper surface.

In attaching the device to the rail the 15 bolster casing is provided with its washer 28 and put through the opening 11, and the washer 29 and nut 33 are applied from below to hold it. The whole device may be levelled up so that it comes exactly vertical. 20 Then the nut is tightened up to hold it positively in that position. This is possible on account of the fact that the hole or perforation 11 is larger than the intermediate portion 17 of the bolster casing, so as to allow 25 some play. Also, on account of the conical or spherical surfaces of the washers, the casing can be tilted slightly until it is brought into an exactly vertical position. This is an 30 important feature because it does away with the continual replacement of the wooden or paper shims heretofore necessary to slightly tip the bolster casing into an exact 35 vertical position. My construction permits the casing to be brought into an exactly vertical position and positively held there.

In operation the plate 20 rests on the horizontal top of the cup 18 and holds the doffer guard 27 in proper position. The spindle, on being inserted, automatically and unresistingly tilts the doffer guard out of its 40 path, rocking plate 20 about the edge of the cup 18 as an axis, on account of its flanges engaging slantingly the upper surface of the doffer guard and because of the freedom of 45 motion allowed by the slots 24. But when the device is placed in position the doffing of the bobbins from the spindle by the attendants cannot accidentally raise the spindle nut of the bolster casing because of the 50 presence of the doffer guard in the position shown in the first two figures. This engages the upper flange 32 if the same is raised far enough and any further vertical movement of the flange 32 causes the doffer hook 55 27 to advance toward the spindle and increase its hold on the flange. This peculiar and very desirable action of the hook occurs by reason of the vertical play allowed the studs 23 in the slots 24. If, 60 however, it is desired to take the spindle out, the operator presses outwardly on the doffer guard 27 as shown in dotted lines in Fig. 5, and the doffer plate will rock about the opposite edge of the cup 18 as an axis. 65 On account of the fact that it is mounted

loosely in this way this plate 20 rests normally in a horizontal position and if displaced in either way it will, on being released drop back to the cup at once by gravity.

Furthermore, the lower flange 30 on the 70 whirl extends down through the opening 22 in the plate 20 and the plate itself minimizes the splashing of oil caused by its flange. Any oil that flows over the top of the bolster 75 casing will run down into the oil cup and be used again in oiling the spindle, and any oil that is put in the cup intentionally can also be used in the same way.

In this way, it will be seen, a bolster casting is provided which can be manufactured inexpensively in larger quantities, one in which no separate member has to be applied for providing the oil cup, and in which the doffer guard cannot by itself get out of the 80 position in which it is always ready to perform its function, because the doffer guard plate 20 returns by gravity to its normal horizontal position when any force applied to it is removed. It will be seen also that the bolster casing can be adjusted vertically to the finest desired degree and accurately and positively held in position. Bolster casings made of sheet metal drawn into the 85 shape shown are oil tight and not porous as 90 in the case of many of the cast iron ones on the market. No oil, even kerosene, can leak through it, as it has no blow holes.

Although I have illustrated and described only a single form of the invention I am 100 aware of the fact that many modifications can be made therein without departing from the scope of the invention as expressed in the claims. Therefore, I do not wish to be limited to the details of construction herein shown and described, but what I do claim is:—

1. As an article of manufacture, a spinning spindle bolster casing comprising a hollow body formed of sheet metal having a cylindrical portion at each extreme end, and an intermediate portion between them formed from the same piece of sheet metal and having an oil conducting enlargement 110 surrounding the casing at the top of said intermediate portion and formed of two thicknesses of the sheet metal in contact with each other and integral with the upper and intermediate portions.

2. As an article of manufacture, a spinning spindle bolster casing formed of a piece of sheet metal and having a bottom closed end, a top open end, an intermediate portion between them having a larger interior diameter and provided with an integral 120 cylindrical enlargement surrounding the bolster casing at a point adjacent to the top of said enlarged intermediate portion and adapted to receive any oil discharged over 125 the top of the open end, and provided with 130

an oil passage through the wall of the sheet metal at the bottom of said cup to discharge the oil into the enlarged portion below.

3. As an article of manufacture, a spinning spindle bolster casing comprising a hollow body having the lower end closed and the upper end open, and an intermediate portion having a larger internal diameter all integrally connected and provided at a point distant from the top with an outwardly extending wall directly connected with the top of said intermediate portion, said wall extending upwardly at the exterior to form an outer cup-shaped wall and then over and in downwardly in contact therewith and then inwardly and integrally connected at its inner part with the upper end of the bolster casing to form an annular space around the casing to receive oil.
- 10 4. As an article of manufacture, a spinning spindle bolster casing comprising a hollow body closed at the bottom and open at the top, and an intermediate portion all formed of sheet metal and provided at a point distant from the top with an outwardly extending wall directly connected with the top of said intermediate portion, said wall extending upwardly at the exterior to form an outer cup-shaped wall and then over and in downwardly in contact therewith and then inwardly and integrally connected at its inner part with the upper end of the bolster casing to form an annular space around the casing to receive oil, said outwardly extending wall of the casing having a convex bottom surface.

5. As an article of manufacture, a spinning spindle bolster casing comprising a hollow body having an intermediate portion and all formed of a single piece of sheet metal and provided at a point distant from the top with an outwardly extending wall extending upwardly at the exterior to form an outer cup-shaped wall and then over and in downwardly and inwardly to form an annular space around the casing to receive oil, the bottom of said outwardly extending wall having a convex form underneath, a rail on which said bolster casing is adapted

to be fixed, and a washer having a concave top resting on said rail and surrounding the intermediate portion of the bolster casing on which washer the convex under surface of the bolster casing rests and fits, and means at the bottom for fastening the bolster casing to the bottom of the rail.

6. As an article of manufacture, a spinning spindle bolster casing comprising a hollow body all formed of a single piece of sheet metal and provided at a point distant from the top with an outwardly extending wall, the bottom of said outwardly extending wall having a convex form underneath, a rail on which said bolster casing is adapted to be fixed, a washer having a concave top resting on said rail and surrounding the bolster casing on which washer the convex under surface of the bolster casing rests, a nut on the bolster casing which is provided with a screw thread below the rail, said nut having a concave upper surface and a convex washer between the nut and the bottom of the rail, said rail having an opening therethrough larger than the bolster casing, whereby the bolster casing can be tilted on the washer to bring it to exact vertical position and the nut can be tightened to hold it in that position.

7. As an article of manufacture, a spinning spindle bolster casing having a wall extending outwardly and provided with a convex form underneath, a rail on which said bolster casing is adapted to be fixed, a washer having a concave top resting on said rail and surrounding the intermediate portion of the bolster casing on which washer the convex under surface of the bolster casing rests, means at the bottom for fastening the bolster casing to the bottom of the rail, the rail having a passage therethrough for the bolster casing larger than the casing, the bolster casing being threaded below the rail, and a nut on it for holding it, the sheet metal washer below the rail engaging the nut and the rail.

In testimony whereof I have hereunto affixed my signature.

HJALMAR G. CARLSON.
